Inventor:

George R. K. Smith.

United States Patent Office.

GEORGE R. K. SMITH, OF BROOKLYN, NEW YORK.

Letters Patent No. 78,132, dated January 7, 1868.

IMPROVEMENT IN WAGON-PROTECTOR.

The Schedule referred to in these Letters Patent and making part of the same.

TO ALL WHOM IT MAY CONCERN:

Be it known that I, GEORGE R. K. SMITH, of the city of Brooklyn, county of Kings, and State of New York, have invented a new and improved Mode of Guarding and Protecting Wagons, Carts, and other Vehicles from the depredations of thieves, pilferers, and other evil-disposed persons. I do hereby declare that the following is a full and exact description thereof, reference being had to the accompanying drawing, and to the letters of reference marked thereon, in which—

Figure 1 represents a front elevation of wagon, wherein A represents the front of wagon; B, horizontal rods across front of wagon; C, lever for operating said rods B; D, centre-pin, on which lever C works; E, staples, through which rods B slide; F, joint which operates rods B, by action of lever C; G, end of side rods, containing points, barbs, rods, nets, webs, or other protuberances; H, side rods, containing points, barbs, rods, &c.; I, connecting-rods, which move side rods H; J, studs, which hold side rods H in their places; K, points, barbs, rods, nets, webs, or other protuberances; L M, incline plane and pin.

Figure 2 represents a plan or top view. Similar letters represent like parts.

Figure 3 represents a side elevation, showing the longitudinal position of said rods H and points or guards K.

Figure 4 represents a front elevation similar to fig. 1, with lever C reversed in the direction of arrow, closing the points or guards K to the side of wagon, out of harm's way.

Figure 5 represents a longitudinal view of side rods H, showing the points or protecting-guards K, location of studs J, and connecting-rods I.

Figure 6 represents the toggle-joint on the ends of connecting-rods B, which give motion to side rods H.

Figure 7 represents the position of incline plane L, and pin M, which operate the front projecting points, and cause them to elevate or depress.

Figure 8 represents a plan and elevation of the incline plane L and pin M.

I construct and attach my invention to the wagon as follows: To the front wagon-box A, I firmly secure a pin, D, upon which moves the lever C, to which I attach connecting-rods B, at F, fig. 1, said rods B being made with forked ends, as seen at fig. 6, the other end of rod B being connected with crank at I, said cranks or connecting-rods I being firmly secured to the ends of side rods H, these last rods, H, being attached to the side of wagon-box by means of studs J, these studs, represented at fig. 5, having an eye sufficiently large to admit of the side rods H turning freely in the studs. These side rods H have inserted throughout their entire length a row of points or barbs, as seen at fig. 5. I also insert a row of points or barbs, or other protuberances, at the top edge of the tail-board, which moves with the tail-board, when it is let down out of the way for loading or other purposes. I also arrange a set of points, barbs, or other projections, in front of the wagon, which is either permanent, as in the case of the tail-board, or suspended in studs J, like the side rods H, fig. 5, these points being operated upon by the incline plane L and pin M, figs. 4, 7, and 8; said inclined plane being secured to the horizontal rod B, and moving in the required direction by the motion of lever C, figs. 4 and 7, thus forming around the wagon a complete barricade, protecting the contents from harm or loss.

Operation: By moving lever C to the left, in the direction of the arrow, fig. 1, the rods B move in towards the centre of wagon through staples E. The outer ends of rods B being attached to connecting-rods I, turn the side rods H on their centres, by which motion the points or other projections K, being firmly secured to side rods H, are lowered to the side of wagon out of harm's way, as seen at fig. 4, or the reverse, as the case requires. The incline plane L, attached to the rod B, acting upon or under the pin M, lowers or elevates the points K in front of the wagon, thus presenting a pointed barricade entirely around the wagon, protecting the contents from harm or loss.

I do not confine myself to points only, but, if occasion requires, may attach a web or net work, in whole or in part, operated as herein described.

What I claim, is—

The construction, application, and arrangement of a protecting-guard, substantially as and for the purposes described.

Witnesses:

G. HARSIN,

GEORGE P. CLARKE.

GEORGE R. K. SMITH.
